UNITED STATES PATENT OFFICE.

FRANCOIS RICHARD AND THOMAS B. RITCHIE, OF CLEVELAND, OHIO, ASSIGNEES TO
THE RICHARD AUTO MFG. COMPANY, OF CLEVELAND, OHIO.

AUTO-TOP.

1,239,265.

Specification of Letters Patent. Patented Dec. 31, 1918.

Application filed February 3, 1917. Serial No. 146,348.

To all whom it may concern:

Be it known that we, FRANCOIS RICHARD, a citizen of the French Republic, and THOMAS B. RITCHIE, a citizen of the United States of America, residing at 7800 Finney Ave., city of Cleveland, in the county of Cuyahoga and State of Ohio, have invented a new and useful Improvement in Auto-Tops, of which the following is a specification, the principle of the invention being herein explained and the best mode in which we have contemplated applying that principle, so as to distinguish it from other inventions.

This invention is associated with an automobile top and more particularly with a top of the single supporting bow type—indeed it may be styled a single bow top because readily manipulated by one immature person.

Our object has been to contrive a structure of the character stated which will be light in weight yet sufficiently strong and rigid, which will permit of being adjusted to become neatly stretched and which will afford a minimum of obstruction of the vision of persons seated therebeneath.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

Adverting to the drawings:

Figure I is a side elevation of the upper part of an automobile body equipped to support a top partly dotted embodying our invention.

Fig. II is a top plan of the top by itself certain underlying parts appearing in dotted lines.

Fig. III is a rear elevation of Fig. I.

Fig. IV is a section on line IV—IV of Fig. I.

Fig. V is an enlarged detail of a portion of Fig. IV.

Fig. VI is an enlarged detail of certain duplicated portions of Fig. IV.

Fig. VII is an enlarged detail showing the manner of front or wind shield attachment.

Figs. VIII and IX are enlarged detail

views of an adjustable strap for securing the supporting bow at the rear, seen from rear 55 and side.

Fig. X illustrates one specific detail.

The Fig. I in the drawings illustrates upper portion of a touring body 1 which has surmounted over its cowl a conventional type of wind shield 2 provided at either side with a socket 3 and a transversely inserted knurled set screw 4, the latter arrangement being more clearly shown in Fig. VII. Pivoted to the top of the frame on each side of the seat at 5 is a supporting bow 6. This bow is of strong metallic structure and assumes the rearwardly oblique position seen in Fig. I when the top is in its raised or functionating position. It will be noticed that its angle of obliquity may be about forty-five degrees in which position it offers no obstruction to the forward nor even the latterly directed vision of the hindmost occupants of the car. Near its upper angles the bow 6 is provided on each side of the vehicle with an eyelet clamp 7 and immediately of the two eyelets 7 are five equi-spaced downward directed eyelets 8 more clearly to be seen in Figs. III and VIII.

The top proper is a composite structure which according to our invention is free from longitudinally extending rigidity because relying solely upon suspension cables. The structure includes in front a wooden block 9 carrying on opposite ends a stud 10 adapted to be inserted in the sockets 3 and secured therein by tightening the screws 4. The construction of the top furthermore comprises a series and in the exemplification are shown four suspended cross bows 11. Connecting the supporting bow 6 with the block 9 and with each of the cross bows 11 are a series of cables some of which are affixed to the cross bows 11 and others of which are movable thereacross. A pair of cable lengths 12 connect the eyelets 7 with corresponding ends of the cross bows 11 respectively to each of which latter they are fixed by suitable clamps 13 as may be seen in Fig. V. A pair of complementary cable lengths 14 additionally connect the angles or corners of the bow 6 with each of the cross bows 11 and necessarily somewhat higher up, in fact along a line which converges in a forward direction toward the line of the cable lengths 12.

to meet around a sheave. The cables 14 are also fixed to each of the cross bows 11 by means of a different type of clamp 15 as is also apparent from inspection of Fig. V. 5 The forward pairs of ends of the cables 12 and 14 are attached to the turnbuckle 16 which is in turn secured in any approved manner to the rear side of the block 9. By means of the turnbuckle 16 the cables 12 and 10 14 may be tightened prior to tightening of the clamps 13 and 15 preparatory to a final proper spacing and set-up of the whole in order to insure of a uniform distribution of the stresses to be later encountered. Connected 15 with the substantially horizontal upper portion of the supporting bow 6 near or at the three points where the eyelets 8 are affixed are three longitudinal extending cables 17 each of which is movable in a 20 metallic groove 18 formed in a plate to be secured to the bow 6 as is clearly shown in Fig. VI. The cables 17 extend in a nearly parallel direction across each of the cross bows 11 and are loosely confined relatively 25 thereto by clamps 19 as may be seen in Fig. V. The forward ends of the cables 17 are fixed in any approved manner to the block 9.

Overlying all the bows and cables is a 30 waterproof covering 20 having a rear downward extension 21 which may be attached to the body by clasp buttons or otherwise. Underneath the covering 20 is an oblique net work cross-bracing 22. To assist in effecting a neat, uniformly taut relationship 35 of the several parts means are provided for counter adjusting the permanent position to be assumed by the supporting bow 6 when elevated, which means consists here of three straps 23 and three buckles 24 which adjustably connect the eyelets 8 with three snap hooks 25 adapted to engage with eyelets 26 fixed to the rearmost top of the vehicle body.

As is apparent the coöperation of the 40 cables some of which coact to properly space and maintain the cross-bracing operates to insure a sufficiently stiff yet somewhat yielding top so that while the whole is precluded from sagging due to what resembles the 45 cantaliver principle of support it is nevertheless capable of yielding to a severe and continuous vibration to which it is likely to become subjected. In some instances it may be desirable to lend additional support by 50 means of a pair of rods 27 one of which is shown in dotted lines in its functioning position in Fig. I. Such rods may be pivoted near opposite ends of that one of the bows 11 which is above the back of the 55 front seat and thereby enable it to be swung down and secured in any suitable manner to the car body.

We claim:

1. An automobile top comprising a single 60 bow pivoted to the rear of the body of the

vehicle and adapted to afford support at the rear, a composite structure adapted to extend between the free end of said bow and the conventional wind shield, said structure including; a rigid front block, adapted for 70 attachment to said shield cables extending between said block and bow and means for tightening said cables.

2. An automobile top comprising a bow 75 pivoted to the body of the vehicle and adapted to afford support at the rear, a composite structure including a series of cross bows and a covering, the whole adapted to extend between the free end of said bow and the conventional wind shield, said structure including lateral pairs of cables extending from end to end, and means for simultaneously tightening the cables of each pair.

3. An automobile top comprising a bow 85 pivoted to the body of the vehicle and adapted to afford support at the rear, a composite structure adapted to extend between the free end of said bow and the conventional wind shield including a series of 90 spaced cross bows, said structure including cables secured to each cross bow and extending from end to end, oblique braces, a covering, and means for tightening said cables whereby to space and stiffen the whole. 95

4. An automobile top adapted to be supported at only one end on the cantaliver principle and comprising a rear bow, a rigid front block, a series of longitudinally extending cables between said bow and block, 100 cross bracing connecting said cables, a covering, means for adjusting the position of said bow relatively to said block to span the entire structure, and distinct means for effecting a relative adjustment of said cross brac- 105

5. An automobile top adapted to be supported at each end and comprising a series of longitudinally extending cables, cross bracing fixed to said cables, a covering, and 110 plural means for tightening said cables and for simultaneously tightening distinct pairs of said cables.

6. An automobile top adapted to be supported at each end and comprising a series 115 of longitudinally extending cables, cross bows fixed to some of said cables, a covering for bows and cables, means for tightening all of said cables, and distinct means for tightening such of said cables as are fixed 120 to said cross bows.

7. An automobile top adapted to be supported between a firm windshield in front and a movable supporting bow in the rear and comprising a series of longitudinally 125 extending cables, suspended cross bows connected with said cables, a covering for bows and cables, means for adjusting the position of said supporting bow whereby to tighten all of said cables and means for tightening 130

certain of said cables by themselves and irrespective of the position of said supporting bow.

8. An automobile top adapted to be supported between a firm wind shield in front and a movable supporting bow in the rear and comprising a series of longitudinally extending cables, suspended cross bows fixed to said cables, a covering for bows and cables, means for tightening all of said cables together, and distinct means for tightening other cables separately.

9. An automobile top comprising the combination with a vehicle body, of a single supporting bow pivoted near the rear end thereof, and a forwardly projecting structure attached to the front and rear of said body and extending over said bow, said structure including; longitudinally extending cables, cross bows holding said cables in spaced relation, and means for effecting a spanned relation of the parts whereby the cantaliver principle of single point support is utilized.

10. An automobile top comprising a bow pivoted to the automobile body and adapted

to afford adjustable support at the rear thereof; a composite structure adapted to extend between the middle portion of said bow and the conventional wind shield at the front of the automobile body, said structure including; a rigid front block, cables extending between said block and pivoted bow, cross bows suspended from and adapted to space apart said cables, said bows being fixed to some of said cables and loosely connected with others thereof, and means for adjusting said bows relative to said block whereby to adjust said suspended bows relative to each other and thus span the structure as a whole.

11. An automobile top adapted to be supported at each end and comprising a series of longitudinally extending cables, cross bows fixed to said cables, a covering for bows and cables, means for tightening all of said cables together, and distinct means for tightening other cables separately.

Signed by us, this 29th day of January, 1917.

FRANÇOIS RICHARD.
THOMAS B. RITCHIE.
